UNITED STATES PATENT OFFICE.

ROGER S. PEASE, OF ALLEGHENY, PENNSYLVANIA.

RAILWAY-TIE.

No. 892,762.

Specification of Letters Patent.

Patented July 7, 1908.

Application filed April 25, 1907. Serial No. 370,158.

To all whom it may concern:

Be it known that I, ROGER S. PEASE, a citizen of the United States, residing at Allegheny, in the county of Allegheny and State 5 of Pennsylvania, have invented certain new and useful Improvements in Railway-Ties, of which the following is a specification, reference being had therein to the accompanying drawing.

10 My invention refers to improvements in railway ties, and consists of a tie composed of sheet or plate metal bent into box form to provide a broad supporting bottom, upwardly and outwardly diverging sides terminating in rail-supporting flanges separated a considerable distance apart so as to approximate in position that of two ordinary ties. By such construction I provide in a single 15 element a practically double tie, thereby reducing the necessary number of ties in a road bed fifty per cent.

20 The tie as thus formed is possessed of great strength, while providing a considerable amount of resiliency or cushioning support 25 for the rails and when embedded in the ballast, forms a strong substantial support therefor.

25 Referring to the drawings:—Figure 1 is a view showing two ties in end elevation with a portion of the rail supported thereon. Fig. 30 2 is a plan view of Fig. 1, portions of the ties being broken away. Fig. 3 is a longitudinal sectional view throughout the full length of a tie indicated by the line III, III, of Fig. 2. Figs. 4 and 5 are similar views showing modified 35 arrangement of the bracing devices. Fig. 6 is an enlarged cross sectional view of the tie, showing adjusting turn-buckle. Fig. 7 is a detail view showing a modified form of 40 bolt for the turn-buckle. Fig. 8 shows a further modification for the purpose of positively holding the rail down upon the flange. Fig. 9 is a detail view showing an outwardly disposed rail-supporting flange.

45 The tie proper consists of a single sheet or plate metal blank, the middle portion 2 of which is flat and provides a broad bottom bearing portion adapted to rest upon the ballast of the roadway.

50 The blank from which the tie is formed is bent upwardly at each side and disposed in outwardly sloping sides 3, 3, which in turn are bent inwardly or outwardly at their upper portions, providing the rail-supporting

flanges 4, 4, extending toward or from each 55 other parallel with base 2 and forming the rail-supporting elements.

Ordinarily the rails are merely laid or set upon these flanges 4 without any direct attachment to the flanges themselves, although 60 such attachments may be employed if desired, as by bolts, retaining lips or other means; but my object is to so connect the rails to the lower portion of the tie that the connecting elements will be covered and protected. 65

In the drawings, I have shown one form of rail-retaining element consisting of a longitudinally disposed bar 5, one or more of which may be employed with each tie, said bars being secured to the bottom 2 of the tie by riveting or bolting or otherwise as indicated at 70 6. The bars extend upwardly and outwardly towards each end from such point of attachment and are provided with rail-engaging 75 terminals 7 having inwardly turned lips 8, 8, at each side adapted to embrace the rail flanges, as clearly shown. By such construction, when the rails are in position and embraced by the bars, they will be held 80 down to their seats, and when the interior cavity of the tie is filled with ballast and the tie itself is completely embedded therein, it will be seen that the bars 5 are entirely covered and concealed, thereby rendering their 85 removal or accidental breakage difficult and improbable. An especial advantage of this construction is that it prevents tampering with the tracks and unauthorized disengagement of the rails from the ties. 90

As shown in Fig. 8 the shoes 7 of bars 5 may, if desired, be provided with a laterally projecting lug 9 adapted to engage underneath flange 4, thereby positively holding the rail directly to its seat. 95

It will be noted that the outwardly diverging sides 3 will bear upon the lower surrounding ballast of the road bed, greatly assisting their stability and load supporting strength.

A further feature of novelty and advantage 100 consists in the means which I have provided for drawing the sides 3 inwardly toward each other so as to adjust the position of the flanges 4, and at the same time brace the sides 3 against outward spreading under 105 the load. This is done by means of bolts 10, 10, passing through the sides 3 and engaging them by their heads 11, or in any other suit-

able manner, as by eyes, said bolts being oppositely threaded at their inner terminals and engaged by turn-buckle 12, lock nuts also being used at the ends of the turn-buckle, if desired. By this construction it will be seen that the sides may be adjusted and rigidly held with relation to each other, and that such adjusting mechanism, being also covered by the ballast, is protected from 10 disarrangement or unauthorized operation. The holding bars 5 may be in the form of a single bar as shown in Fig. 3; or double bars 5' may be employed, either lapping over each other and secured to the bottom, as indicated at 6'; or they may have separate attaching connections, as indicated at 6", Fig. 5. The form of construction of said bars may be changed or varied as by the use of different rail-embracing terminals, while various other changes or modifications may be made in the design, construction, or other features of the invention by the skilled mechanician. If desired the bottom 2 may be corrugated transversely, or perforated, or provided with suitable flanges or other devices for engaging in the ballast to more securely anchor the tie in place.

Having described my invention, what I claim is:—

30 1. In a railway tie, the combination of a plate metal blank bent to provide a bottom portion and upwardly extending sides having terminal rail supporting flanges parallel with the bottom portion, and retaining bars 35 secured to the inner middle bottom portion of the tie extending upwardly and outwardly in opposite directions and having rail embracing terminals located substantially on a level with the rail supporting flanges and provided with outer and inner inwardly turned 40 lips adapted to embrace the rail flanges when in position, substantially as set forth.

2. A railway tie consisting of a plate metal blank bent to provide a bottom portion, and 45 upwardly and outwardly diverging sides having terminal rail-supporting flanges, retaining bars secured to the inner middle bottom portion of the tie extending in opposite directions and having terminals for engaging 50 the rails, and braces connecting the opposite sides of the tie, having tightening devices, substantially as set forth.

3. A railway tie consisting of a plate metal blank bent to provide a bottom portion, and 55 upwardly and outwardly diverging sides having terminal rail-supporting flanges, rail securing bars secured to the middle bottom portion of the tie and having rail-embracing terminals adapted to engage and hold both 60 flanges of the rail, and means connecting the

opposite middle portions of the sides of the tie, substantially as set forth.

4. In a railway tie, the combination with a trough shaped plate metal body having a bottom, sides and rail-supporting flanges, of rail 65 retaining bars secured to the bottom of the middle portion of the tie, extending outwardly towards each opposite end of the tie, and provided with oppositely directed flange-embracing upturned terminals adapted to 70 engage and hold both flanges of the rails, substantially as set forth.

5. A plate metal railway tie bent into trough shape, having a flat bottom, upwardly and outwardly diverged sides, inwardly disposed rail-supporting flanges parallel with the bottom, transverse braces connecting the sides, and a single continuous longitudinal holding bar secured to the bottom portion of the tie and having oppositely directed terminals adapted to embrace the rail flanges at each edge, substantially as set forth.

6. In a railway tie, the combination with a trough-shaped plate metal body having a 85 bottom, sides and rail supporting flanges, of rail-retaining means secured to the bottom of the tie having rail-embracing terminals and uplift-preventing devices engaging the flanges, substantially as set forth. 90

7. A plate metal railway tie bent into trough shape having a flat bottom, upwardly and outwardly diverging sides, inwardly disposed rail-supporting flanges parallel with the bottom, means connecting the sides, and 95 a longitudinal holding bar secured to the bottom portion and adapted to embrace the rail flanges, substantially as set forth.

8. The combination with a trough-shaped plate metal tie having upwardly extending 100 sides, of transversely arranged turn-buckles and securing bolts engaging the opposite sides of the tie, substantially as set forth.

9. The combination with a trough-shaped plate metal tie having upwardly extending 105 sides, of holding means secured to the bottom of the tie, extending outwardly and upwardly in opposite directions, and provided with flange-embracing terminals having oppositely arranged inwardly disposed lips, and means adapted to engage the tie to prevent upward movement of the terminals, substantially as set forth.

In testimony whereof I affix my signature in presence of two witnesses.

ROGER S. PEASE.
